(57) **CLAIM**

The ornamental design for a passenger information module with touch screen graphical user interface having a set of screens, as shown and described.

DESCRIPTION

FIG. 1 is a perspective view of the passenger information module in which a set of interface screens of the touch screen graphical user interface of the claimed design is embodied. FIG. 2 is a front view of the trip start interface screen of the touch screen graphical user interface of the claimed design. FIG. 3 is a front view of the display interface screen with channel guide of the touch screen graphical user interface of the claimed design.

FIG. 4 is a front view of the news interface screen with topic levels of the touch screen graphical user interface of the claimed design.

FIG. 5 is a front view of the route map interface screen with channel column map of the touch screen graphical user interface of the claimed design.

FIG. 6 is a front view of the enlarged route map interface screen of the touch screen graphical user interface of the claimed design.

FIG. 7 is a front view of the payment interface screen of the touch screen graphical user interface of the claimed design.

FIG. 8 is a front view of the cash payment interface screen of the touch screen graphical user interface of the claimed design.

FIG. 9 is a front view of the tip interface screen of the touch screen graphical user interface of the claimed design; and, FIG. 10 is a front view of the credit card payment interface screen of the touch screen graphical user interface of the claimed design.

The dashed lines in FIG. 1 show the environment, and form no part of the claimed design. The dashed lines in FIGS. 2-10 illustrate portions of the touch screen graphical user interface and form no part of the claimed design. The perimeters of FIGS. 2-10 represent the edge of the touch screen in the passenger information module. The claimed design is directed to the collective appearance of the set of interface screens of the touch screen graphical user interface.
